Second Patent

May 28, 1816 2605X
The substance referred to in these Letters Patent and making part of the same containing a description in the words of the said David Beard himself of his improvement in blocking hats. The above machine consists of four pieces of wood and three pieces of iron. Two of the pieces of wood are twenty two inches long and two and a half inches wide, flat on one side, and rounding on the other, with a mortise through each of them, about five inches from one end in these mortises is set an iron bar nineteen inches long and seven eights of an inch wide with four holes through it about one inch apart from the middle to one end which end goes through one of the aforesaid mortised wood and holds to its place by a spring bolt fastened on the side of the piece of wood, for the purpose of making the machine wider or narrower. The other end of the bar is riveted into the other mortise. Between the wooden bars is a iron tongue, and plays loose on the iron bar, on the end of which tongue rests three pieces of wood of different lengths and separately, as occasion requires, as the aforesaid bars are made wider or narrower. By means of which machine the top of the hat is stretched out. The last being fast on the ground the machine set perpendicular, is moved by forcing the upper ends of the aforesaid wooden bars together, which of course widens the lower ends and prepares the hat for the blocks.
